[57] CLAIM

The ornamental design for a counter-top water filter, as shown and described.

DESCRIPTION

FIG. 1 is a perspective view of a counter-top water filter showing our new design;

FIG. 2 is a left side elevational view thereof;

FIG. 3 is a right side elevational view thereof;

FIG. 4 is a front elevational view thereof;

FIG. 5 is a top plan view thereof; and

FIG. 6 is a top plan view thereof, the cover omitted for clarity of illustration.
